UNITED STATES PATENT OFFICE.

CHARLES W. DAKE, OF GRAND RAPIDS, MICHIGAN, ASSIGNOR TO THE DAKE-AMERICAN STEAM TURBINE COMPANY, OF GRAND RAPIDS, MICHIGAN, A CORPORATION OF MICHIGAN.

GOVERNOR FOR TURBINES.

No. 880,366.

Specification of Letters Patent.

Patented Feb. 25, 1908.

Application filed March 22, 1906. Serial No. 307,461.

To all whom it may concern:

Be it known that I, CHARLES W. DAKE, a citizen of the United States, residing at Grand Rapids, Michigan, have invented certain new and useful Improvements in Governors for Elastic-Fluid Turbines, of which the following is a specification.

This invention relates to improvements in governing devices for elastic fluid turbine engines, although the same means might be made use of for governing other types of engines. The same is especially well adapted for the turbine variety of engines, and I have shown the same only in that relation.

15 The objects of the invention are, primarily, to provide a very sensitive governor for elastic fluid turbine engines.

Further objects, and objects relating to details of construction, will definitely appear 20 from the detailed description to follow.

I accomplish the objects of my invention by the devices and means described in the following specification.

The invention is clearly defined and 25 pointed out in the claims.

A structure embodying the features of my invention is clearly illustrated in the accompanying drawing forming a part of this specification, in which—

30 Figure 1 is a view of a turbine engine, a portion of which is broken away, with my improved governor illustrated in position on the main shaft thereof. Fig. 2 is an enlarged detail vertical sectional view through 35 the governor showing also detail of attachment to the casing; and Fig. 3 is a plan view of the top-plate of the governor, with the electric binding posts thereon, the wiring not being indicated in Figs. 2 and 3.

40 In the drawing, similar numerals of reference refer to similar parts throughout the several views.

Referring to the numbered parts of the drawing, the main casing 1 of the governor is 45 secured above the central axis of a turbine engine of the vertical type. This casing is provided with a cap 2 on which are suitable binding posts 3—3 insulated therefrom, the inner ends of the said binding posts projecting 50 down to different levels within the casing. Each binding post is made up of a central screw-threaded stem 30 which is adjustable up and down as desired, through a bushing 32, the same being separated from the plate 55 2 by a suitable insulating material 8. A washer 31 is on top of the insulation, against

which the nut of the binding screw readily clamps the wiring. The binding screws, as before remarked, are of different length and adjust to different elevations around just 60 within the periphery of the chamber beneath. The chamber beneath is funnel-shaped and has, revolving in it, a funnel-shaped receptacle 5' containing perforations 33 in the bottom. This is supported on a central vertical shaft 5 which rests on the insulating material 5" in the upper end of the main engine shaft 4.

The casing 1 is separated by insulating material 1' from the main casing 21 of the 70 casing of the engine and dynamo, this engine illustrated being provided with the dynamo casing above. The shaft 5 is surrounded by a stuffing-box to form a tight joint, a passage 9' is connected to a small cock 9' for drawing 75 the liquid out of the chamber 6. A heavy fluid, 10, such as mercury, is placed within the chamber, and when the engine is at rest, stands in the level position indicated therein. When the parts begin to revolve, however, 80 the centrifugal force depresses the surface at the center, and causes the same to rise at the periphery, and, as the speed increases, this surface becomes more and more depressed at the center and the mercury rises higher 85 and higher towards the periphery of the receptacle. As it raises up, it would, in the first instance, of course, contact with the binding post having the greatest projecting point, and, as the speed increased, it would 90 then contact with the next higher, and so on, until all of these binding posts were brought into contact with the mercury; and, if the motion still continues to increase, the depression of the liquid at the center would of 95 course continue until eventually it ceases to contact with the screw of the central binding post 3', when the circuit would be broken at that point.

Surrounding the receptacle, is a chamber 100 7 for receiving steam from pipe 12 which is controlled by a cock 14, the steam passing out at 11. The steam admitted to the chamber is for the purpose of controlling the temperature of the governing fluid, consequently its density or bulk, this being the most satisfactory means of keeping the same substantially uniform. The dynamo casing of this machine is supported on stands 22 which rest on top of the engine casing 23 110 which rests on the lower plates and structures of the engines 24 and 25.

In the base part 25 of the engine are located valves 19 and 20 for controlling the nozzle sections of the engine. Wires at 15 15 are connected from the binding-posts 3 5 of the governor for controlling the same; and a wire 15' connects the central binding-post 3' to the main supply valve 20.

A source of supply, as a generator, 17, is connected by a circuit 16 to the casing 1 of 10 the governor and at the opposite side is connected by a wire 18, so that when the contact is established between the mercury and the binding-post 3, or is broken between the mercury and the binding-post 3', the valves 15 19 and 20 will be controlled by suitable 20 electro-magnetic devices located therein, and the engine will therefore be under perfect control. I have shown the specific relations of these parts and have not deemed it necessary to illustrate in detail the electro-magnetic means in the valves themselves, as I have shown such in detail in another concurrent application. A battery might be made use of in place of the generator 17 for 25 furnishing the electric current, or any other source of electrical supply, as the main dynamo, could be utilized.

On turbines that run at high speed I am aware that it will be desirable to gear down 30 so as to run the shaft of my improved governor at a lower rate than the usual rate of such engines.

I desire to state that the details of this 35 structure can be greatly varied. I have shown the same in a simple and practical form and have not attempted to illustrate modifications of details of constructions, as I do not deem that necessary.

Having thus described my invention, what 40 I claim as new and desire to secure by Letters Patent is:

1. In a governor for turbine engines, of the vertical type, the combination of the main casing 1 secured at the top of the casing 45 of the turbine and separated therefrom by insulating material 1'; a funnel-shaped receptacle in the upper part of said casing, surrounded by a suitable jacket for receiving and circulating the elastic fluid therethrough 50 and to preserve an even temperature; a funnel-shaped receptacle 5' within the funnel-shaped chamber, having perforations 33 near its bottom, with a downwardly projecting shaft 5 supported on the vertical shaft 4 of 55 the turbine and suitably insulated therefrom by the insulation 5"; a liquid such as mercury within the said chamber and receptacle, adapted to revolve freely therewith; a top-plate 2 for the casing 1, having a series

of binding posts 3 insulated therefrom and 60 projecting to different heights within the periphery of the said plate and receptacle; a central binding post 3', the screw of which projects well down into the center of the said receptacle and beneath the surface of the 65 mercury, as it ordinarily stands therein; a generator for electrical current; a series of 70 governor valves for controlling the supply of steam to the turbine with electro-magnetic devices for controlling the same; and independent circuits from the binding posts 3 to different ones of the series of throttling valves, whereby as the circuit closes on account of increased speed of the turbine, the 75 governor valves will be actuated, co-acting for the purpose specified.

2. In a governor for turbine engines, the combination of a suitable chamber; a receptacle within the same supported on a vertical axis; connections to the engine for 80 revolving the said receptacle; a liquid within the receptacle; independent circuits with contact points arranged towards the periphery of the said chamber, to contact with the liquid therein at different heights as the 85 height varies at the periphery, owing to the centrifugal force developed by its rotary motion; and suitable governor valves connected to be controlled by said circuits, for the purpose specified. 90

3. In a governor for turbine engines, the combination of a suitable chamber; a receptacle within the same, supported on a vertical axis; connections to the engine for revolving the said receptacles; a liquid within 95 the same; an electrical circuit with contact points arranged above the normal level of the said liquid; and a suitable governor valve, with electrical devices for controlling the same, arranged within the said electrical 100 circuit, co-acting for the purpose specified.

4. In a governor; the combination of a suitable chamber; a receptacle within the same, supported on a vertical axis; mercury within the same; an electrical circuit with 105 contact points within the chamber; a governing valve within the said electrical circuit, the current through the said circuit being controlled by the variations of the level of the mercury due to the rotation, co-acting 110 for the purpose specified.

In witness whereof, I have hereunto set my hand and seal in the presence of two witnesses:

CHARLES W. DAKE. [L. s.]
